Patented Mar. 19, 1918.

WITNESS:

R. Hamilton

INVENTOR,
W. E. Minton,
BY Chas. W. Gerard.

ATTORNEY.

UNITED STATES PATENT OFFICE.

WILLIAM E. MINTON, OF KANSAS CITY, MISSOURI.

WELL-CLEANING DEVICE.

1,260,241.

Specification of Letters Patent. Patented Mar. 19, 1918.

Application filed January 17, 1918. Serial No. 212,347.

To all whom it may concern:

Be it known that I, WILLIAM E. MINTON, a citizen of the United States, residing at Kansas City, in the county of Jackson, State 5 of Missouri, have invented certain new and useful Improvements in Well-Cleaning Devices, of which the following is a specification.

The present invention relates to pumping 10 apparatus and aims to provide an improved means for cleaning away the sand, shale, paraffin and other material which collects at the bottom of the well around the end of the pump tube,—particularly in oil well 15 pumping. One of the principal objects of the invention, therefore, is to devise a construction adapted to utilize a flow of liquid for washing out the deposits of material which collect at the points referred to, and 20 thus afford room for the oil or liquid being pumped to flow into the bottom of the pump. Where a sand screen or strainer is used at the lower end of the well casing, it is also sought to provide a device which will 25 thoroughly wash and clean both the inner and outer faces of this screen or strainer. A still further object is to utilize a liquid flow for cleaning out the sand and other material in such a manner that the deposits 30 of such material will be carried on up out of the well by means of the flow of liquid thus established.

Minor objects will appear in the course of the detailed description.

With these general objects in view, the 35 invention will now be described with reference to the accompanying drawing illustrating one form of construction which has been devised for embodying the improvements, after which the novel features thereof will be set forth and defined in the claims appended hereto.

In the drawing—

Figure 1 is a vertical sectional view of 45 the lower end portion of a pumping apparatus with the present improvements applied thereto; and

Figs. 2 and 3 are transverse sections taken on the lines 2—2 and 3—3, respectively, of 50 Fig. 1.

Referring to the drawing in detail, this shows the lower end portion 4 of a well casing, to which may be connected a perforated sand screen or strainer casing 6, 55 as by means of a coupling 8, as illustrated

in Fig. 1. Within the casing 4 is shown the lower end portion of the pump tubing 10, to which is connected, as by a coupling 12, a short tubular nozzle section 14 terminating in a central discharge opening 16 60 above the bottom of the screen or strainer 6, the lower tapered portion of said nozzle section 14 having the lateral but downwardly inclined discharge slits 18 located above said opening 16 and facing at right angles to 65 the lower tapered portion of the screen 6.

Above the slits 18 the cylindrical portion of the nozzle section 14 is formed with a series of discharge slits 20 adapted to discharge outward at right angles to the cylindrical portion of the screen 6. Intermediate the discharge slits 18 and 20, the nozzle section 14 is formed with an exterior annular shoulder 22 against which is fitted a scraper member comprising an inner ring-shaped 70 portion 24 adapted to be clamped against said shoulder 22 by means of a collar 26, and also comprising a series of outwardly extending flexible wings 28 (see Fig. 3) 75 adapted to scrape the inner face of the 80 cylindrical portion of the screen 6. This scraper member may be stamped out of thin sheet metal, leaving open spaces 30 (see Fig. 3) between the several wings 28 for the 85 passage of the liquid flow between the screen and nozzle members.

Above the discharge slits 20, the nozzle section 14 is also formed with an exterior annular shoulder 32 (similar to the shoulder 22) against which is fitted a ring 34 of any 90 suitable packing material embraced between a pair of thin metal washers 36, one resting upon said shoulder 32 and the other adapted to be jammed against the coupling 12 (on attachment of the nozzle section) for 95 holding the parts in the position shown in Fig. 1.

In the operation of the device, water or other suitable liquid is forced down through the pump tubing 10, and thereby ejected in 100 forcible jets out through the discharge opening 16 and the various slits 18 and 20, thus flooding and thoroughly washing the inner face of the screen or strainer 6. When the packing 34 is used, the passage up between 105 the screen and nozzle members is of course cut off, and the flow is obliged to pass outside the screen to reach the level above said packing before it can again enter the space within the well casing by way of the per- 110

forations in the upper end of the screen. By means of the liquid flow thus established outside the screen, the outer face of the latter is thoroughly washed, and the deposits 5 of material outside the screen are loosened up and gradually conveyed out along with the flow of liquid to the top of the well. For further cleaning the inner face of the screen, the pump tubing 10 may be raised 10 and lowered in order to impart a reciprocatory movement to the scraper elements, thereby scouring the screen's inner face and clearing it of paraffin, shale or other clogging material,—in which action the packing 15 material also coöperates in rubbing away the clinging deposits. In case, however, the screen or strainer is not being used, as is the case in some operations, the scraper elements may nevertheless be operated in this 20 manner to loosen up the deposits around the nozzle member, thereby further increasing the effectiveness of the liquid flow as above described.

It will thus be apparent that a simple and 25 efficient arrangement and construction have been devised for carrying out the desired objects of the invention, and while the foregoing illustrates what is now regarded as the preferred form of construction for embodying the improvements, the right is reserved to such formal changes or modifications as may fairly fall within the scope of the appended claims.

What I claim is:

35 1. A well cleaning device comprising, in combination with the pump tube, a nozzle section adapted to be secured to said pump

tube, and a series of flexible scraper elements carried by said nozzle section.

2. A well cleaning device comprising, in 40 combination with the pump tube, a screen member surrounding the lower end portion of said tube, a nozzle section adapted to be secured to the end of said pump tube, said nozzle section being provided with a series 45 of lateral discharge passages, and packing material interposed between said screen and nozzle section above said discharge passages and below the upper end of said screen.

3. A well cleaning device comprising, in 50 combination with the pump tube, a screen member surrounding the lower end portion of said tube, a nozzle section adapted to be secured to the end of said pump tube, and scraper elements carried by said nozzle section 55 and extending into scraping engagement with the inner face of said screen member.

4. A well cleaning device comprising, in combination with the pump tube, a screen 60 member surrounding the lower end portion of said tube, a nozzle section adapted to be secured to the end of said pump tube, said nozzle section being provided with a series 65 of lateral discharge passages, packing material interposed between said screen and nozzle section above said discharge passages and below the upper end of the screen member, and scraper elements carried by said nozzle section and extending into scraping 70 engagement with the inner face of said screen member.

In witness whereof I affix my signature.

WILLIAM E. MINTON.
